Inventor

Robert P. Frye,

By Fauksaareman.

Attorney

UNITED STATES PATENT OFFICE.

ROBERT PRESTON FRYE, OF MARLBORO, MASSACHUSETTS.

MACHINE FOR MAKING SHOE BOXINGS.

1,410,562.

Specification of Letters Patent. Patented Mar. 28, 1922.

Application filed March 18, 1920. Serial No. 366,788.

To all whom it may concern:

Be it known that I, ROBERT P. FRYE, a citizen of the United States of America, and resident of Marlboro, in the county of Middlesex and State of Massachusetts, have invented certain new and useful Improvements in Machines for Making Shoe Boxings, of which the following is a specification.

10 This invention relates to machines for making shoe boxings and has for its object the provision of novel means for applying liquid material which upon drying or cooling will solidify and reenforce or stiffen the 15 fabric in order that it may be used as boxings for shoes, and the invention consists an improvement on my Patent #1,236,832 of August 14, 1917.

The present invention has the objects in 20 view of producing the results and functions of the said patented device but in a more expeditious and satisfactory manner and it furthermore has for its object to provide the novel means whereby the presser 25 head is moved uniformly so as to obviate splashing of the fluid or undue agitation thereof while the presser head is moved into and out of the receptacle.

A further object of this invention is to 30 provide novel means for yieldingly holding the mandrel with relation to which the presser head moves and coacts and to simplify the construction which minimizes the cost of production and maintenance.

35 With the foregoing and other objects in view, the invention consists in the details of construction and in the arrangement and combination of parts to be hereinafter more fully set forth and claimed.

40 In describing the invention in detail, reference will be had to the accompanying drawing forming part of this specification wherein like characters denote corresponding parts in the several views, and in 45 which—

Figure 1 illustrates a sectional view of a machine embodying the invention;

Figure 2 illustrates a front view partly in section;

50 Figure 3 illustrates an underneath plan view of a presser head;

Figure 4 illustrates a sectional view thereof;

55 Figure 5 illustrates a perspective view of the clutch operating lever.

In these drawings 10 denotes a hollow standard having a suitable base or support 11, the said standing having a curved upper end with a marginal flange 12 and a web 13 closing the end of the standard except for the aperture 14 therein, in which a mandrel rod 15 is slidable.

60 A housing comprising a casing 16' has a flange 17 secured to the flange 12 by fastenings 18, such as bolts and the said housing 65 has a transversely disposed web 19 which is apertured to receive the mandrel rod so that the mandrel rod may reciprocate in the housing and in the end of the standard. An apertured plate 20 is secured on the 70 lower end of the housing by fastenings such as screws 21 and a mandrel 16 is carried on the lower end of the mandrel rod.

A collar 22 is secured near the upper end 75 of the mandrel rod and is intended to engage the end of the standard to limit the movement of said mandrel rod and collars 23 and 24 are also secured on the mandrel rod for purposes to be presently explained.

80 A coiled spring 25 is applied to the mandrel rod above the collar 23 and is intended to operate as a buffer or shock absorber when the mandrel rod has traveled a predetermined distance since when the said spring bears against the collar 23 and will upon 85 upward movement of the mandrel rod strike the end of the standard and be compressed.

85 A spring 26 encircles the mandrel rod and bears against the collar 24 and against the web 19 so that the mandrel rod is held normally depressed by the said spring, and when the presser head moves upwardly it 90 communicates motion to the mandrel rod against the action of the said spring 26.

95 A plate 27 covers an aperture 28 in the standard and is secured to the said standard by fastenings 29 such as screws which pass through the plate and are threaded in the standard around the margin of the said plate. Apertured lugs 30 and 31 are carried by the plate and constitute guides for the rod 32 which is slidable in the apertures of the said lugs. The plate 27 has a slot 33 which constitutes a clearance for the arm 34 which arm has an aperture to receive the 100 rod 32 and the said rod is held at different positions of adjustment on the rod by means of the fastening 35 which may be in the nature of a set screw. As the rod 32 is reciprocated the arm is carried up and down 105 110

and the said arm has a downwardly extending portion 36 which dips into the receptacle 37 adapted to contain a solution to be applied to boxings of shoes which solutions when dried or hardened lends stiffness and rigidity to the said boxings.

The depending end 36 of the arm has the presser head thereon which is of improved construction compared with that of the patent and the said presser head of this device differs from that shown in the aforesaid patent in that the shield 92 has flat strips of metal 93 anchored to it at their ends and the said strips of metal extend under the plate 94 of the presser head and the said plate carries the cushion 95 and these parts, except the strips of metal, correspond to the construction of the presser head of the patent, but in this form of invention I interpose springs 95' on the guiding rods 96 between the shoulders 98 and the strips of metal and have the guiding rods 96 on the said plate and connected thereto which travel through apertures 97 in the said strips of metal, the springs in this form yielding under pressure when the presser head is in cooperative relation with the mandrel and the material to be pressed and treated is between the presser head and the mandrel. The springs just described perform somewhat the same function as the springs 26 of the patent.

The rod 32 has a collar 38 attached to it, the said collar being adjustable to different positions thereon according to the throw to be given the rod and the collar is held at such adjustments by a set screw 39. This collar also has a wrist pin 40 projecting from it on which a link 41 is oscillatably mounted, the lower end of the said link being connected to a wrist pin 42 carried with the gear wheel 43. It is the purpose of the inventor to perhaps modify the structural features of the wheel and the illustration shows the preferred embodiment at this time.

A spring 44 encircles the rod 32 and is interposed between the collar 38 and the apertured lug 31 so that yielding action is afforded the rod as it is being reciprocated and, therefore, the presser head will move into the fluid contained in the receptacle without creating agitation or splashing of the fluid.

55 A stud 45 is secured in an aperture 46 of the standard and the said stud constitutes a trunnion on which the wheel 43 is rotatable.

A driven shaft 47 is journaled in suitable bearings in the standard below the stud 45 and the said driven shaft has a pinion 48 secured to it which meshes with teeth of the gear wheel 43 so that through these instrumentalities the gear wheel 43 is rotated.

The driven shaft 47 has a pulley 49 rotatable on it and one face of the said pulley

constitutes a clutch member 50 which is engaged by a clutch member 51, keyed on the shaft 47 so that as the pulley is reciprocated on the shaft, it is caused to engage or disengage the clutch member 51 and as the pulley is to be driven in any suitable manner by a belt or the like, its motion will be communicated to the mechanism of the machine when the clutch members are in engagement. The shaft 47 has a collar 52 secured to it by a fastening 53 such as a screw and said collar limits the motion of the hub 54 of the pulley 49 which hub is of course a part of the pulley and is moved on the shaft by the lever 55 which has a bifurcated end to embrace the hub, the said hub having a reduced portion which is spanned by the bifurcated end of the lever. The lever is oscillatably mounted on a pivot 56 and terminates in a pedal 57 by which it is moved in one direction, the said pedal end of the lever being elevated by a spring 58 which is connected to a stud 59 of the standard and to the said lever.

It will be understood from an inspection of the drawing and from the foregoing description that when power is applied and the pulley is rotated, the presser head will be moved into and out of the receptacle 37 and into and out of coactive relation with the mandrel so that when the material which is to be stiffened for shoe boxings is interposed between the presser head and the mandrel, material carried from the receptacle by the presser head will be forced into engagement with the said material and that the device will operate with sufficient force to cause the material being treated to be impregnated to a great extent by the fluid.

Owing to the yielding action of the fluid carrying presser head and the means for confining a certain amount of the fluid delivered, it is in coactive relation to the material to be impregnated, the degree of efficiency of the fluid applying mechanism is very pronounced, and, of course, any fluid that is dislodged from the presser head or the material being treated finds its way to the receptacle so that there will be no waste.

I have provided a means for maintaining the fluid in the receptacle 37 at a predetermined level and to that end, I utilize a tank 60 having a spout 61 depending or extending into the said receptacle 37 and I have the tank air tight so that it is only by unsealing the end of the spout 61 that air may be admitted. The spout 61 is sealed by the fluid in the receptacle 37 and air sealed in the tank will prevent flow of fluid from the tank until the fluid in the receptacle 37 recedes and again unseals the end of the spout and of course this result in automatic maintenance of the fluid at a predetermined level in the receptacle 37.

The mandrel rod 15 has a slot 15* in it to

receive a screw 15^b which prevents rotation of the mandrel rod while at the same time permitting it to move vertically.

The receptacle 37 is adapted to hold the material which is adapted to be heated and the ordinary electrically heated pots used for this purpose may be substituted for that of the form shown.

The standard has shields A on each side secured to the standard by fastenings B such as screws whereby the gear wheel 43 is shielded although access can be had to the interior of the standard by the removal of the said shields.

15 I claim—

1. In a machine for making shoe boxings, a hollow pedestal having an opening in one face, a slotted plate closing the opening, guides on the said slotted plate, a rod adapted to reciprocate in the said guides, an arm carried by the said rod and extending through the slot of the plate and having a depending portion, a receptacle into which the depending portion of the rod extends, a 25 presser head carried by the said rod, a mandrel, means for yieldingly supporting the mandrel in operative relation to the said presser head, and means for reciprocating the rod.

30 2. In a machine for making shoe boxings, a hollow pedestal having an opening in one side, a slotted plate secured to the said standard for closing the opening, guides on said slotted plate, a rod slidable in the guides, an arm adjustably secured on the said rod and extending through the slot of the plate, a presser head carried by the said arm, a receptacle into which the arm extends, a mandrel, a mandrel rod carrying 35 the mandrel, a guiding device on the end of the standard for the mandrel rod, and means for yieldingly holding the mandrel rod in its lowermost position of adjustment.

3. In a machine for making shoe boxings, 45 a hollow pedestal having an opening in one side, a slotted plate secured to the said standard for closing the opening, guides on said slotted plate, a rod slidable in the guides, an arm adjustably secured on the said rod and extending through the slot of the plate, a presser head carried by the said arm, a receptacle into which the arm extends, a mandrel, a mandrel rod having a slot therein, a member engaging in the slot which will 50 prevent rotation of the mandrel rod, a guiding device on the end of the standard for the mandrel rod, and means for yieldingly holding the mandrel rod in its lowermost position of adjustment.

60 4. In a machine for making shoe boxings, a presser head having a plate, a shield with relation to which the plate is movable, metallic strips extending under the plate and having their ends anchored to the shield,

plate through the said strips, shoulders on the said guide rods, springs interposed between the shoulders and the straps, and an arm connected to the plate for pressing it upwardly.

70

5. In a machine for making shoe boxings, a shield, a plate movable with relation to the shield, and within said shield, a cushion carried by the plate, strips of material extending under the plate and having their ends anchored to the shield, guiding members carried by the plate extending through said strips, and means for yieldably holding the plate at the bottom on said strips.

75

6. In a machine for making shoe boxings, 80 a standard having a curved end, a housing suspended from the end of the standard, a web in the said housing, the said web having an aperture, apertured plates on the housing, a mandrel rod slidable in the apertures 85 of the web and plates, means for yieldably holding the mandrel rod depressed, a mandrel carried by the head, a presser head in operative relation to the mandrel, a member having coating material with relation to 90 which the presser head is operatively mounted and means for moving the presser head with relation to the mandrel.

7. In a machine for making shoe boxings, 95 a hollow standard having an aperture in one side, a plate for closing the opening, said plate having a slot therein, guides on the said plate, a rod slidable in the guides, an arm carried by the said rod, a presser head on the said arm, means for supplying the 100 presser head with a coating material and a mandrel supported in position to coact with the presser head, a collar adjustably secured on the rod, a spring on the said rod interposed between the collar and one of the 105 guides for absorbing shock, a wrist pin on the said collar, a gear wheel rotatably mounted in the standard, means connecting the gear wheel with the wrist pin for reciprocating the rod, a shaft journaled in the 110 standard, a pinion on the said shaft meshing with the gear wheel, a clutch on the said shaft, a power driven wheel rotatable on the shaft and having a clutch member coacting with the clutch member on the shaft, and 115 means for moving the driven wheel into and out of operative engagement with the clutch member.

8. In a machine for making shoe boxings, 120 a pedestal, guides mounted within the pedestal, a rod slidable in the guides, an arm secured on the rod and projecting outside of the pedestal and having a depending portion, a receptacle into which the arm moves, a presser head carried by the arm, means for reciprocating the rod, and a mandrel with 125 relation to which the presser head is movable.

9. In a machine for making shoe boxings, 130 a standard, guides therein, a rod slidable in

the guides, an arm adjustably secured to the rod, said rod extending outside of the standard and having a depending portion, a receptacle into which the depending portion extends, a presser head carried by the said arm, a mandrel with relation to which the presser head moves, a collar on the rod, a spring interposed between the collar and one of the guides, and means for reciprocating the rod.

10. In a machine for making shoe boxings, a standard, guides therein, a rod slidable in the guides, an arm adjustably secured to the rod, said rod extending outside of the standard and having a depending portion, a receptacle into which the depending portion extends, a presser head carried by said arm, a mandrel with relation to which the presser head moves, a collar on the rod, a spring interposed between the collar and one of the guides, a gear wheel rotatably mounted in the standard, means for communicating the

motion of the gear wheel to the rod for reciprocating the rod, a shaft journaled in the standard and having a pinion engaging the gear wheel, a clutch member secured on the shaft, a driven member rotatable on the shaft and having a clutch member coacting with the first mentioned clutch member, and means for moving the clutch members into and out of engagement with each other.

11. In a machine for making shoe boxings, a standard, a presser head, means associated with the standard for reciprocating the presser head, a member attached to the said standard and having rod guiding devices associated with it, a receptacle for holding coating material into which the presser head is movable, a mandrel, and a mandrel rod slidable in the said member on the standard, whereby the mandrel is held in operative relation to the presser head.

ROBERT PRESTON FRYE.
